(57) CLAIM

(21) Appl. No.: **29/408,587**

I claim the ornamental design for a serving tray with cooling elements for cans, bottles or food, as shown and described.

(22) Filed: **Dec. 14, 2011**

DESCRIPTION

(51) **LOC (9) Cl.** **07-01**

FIG. 1 is a perspective view of the serving tray with cooling elements for cans, bottles or food, showing my new design; FIG. 2 is an exploded perspective view of the serving tray with cooling elements for cans, bottles or food thereof showing the handle in the folded position;

(52) **U.S. Cl.**

FIG. 3 is a front view of the serving tray with cooling elements for cans, bottles or food of FIG. 1, showing the handle in an upright position, the rear view being a mirror image thereof;

USPC **D7/553.6**

FIG. 4 is a top view thereof;

(58) **Field of Classification Search**

FIG. 5 is a right side view of the serving tray with cooling elements for cans, bottles or food, with the rotatable handle in a storage position, the left side view being a mirror image thereof; and,

USPC D7/550.1, 553.1, 553.6, 553.7, 554.2,
D7/566, 586-587; D19/75-79, 95;
206/558-567; 220/574-575

FIG. 6 is a right side view of the serving tray with cooling elements for cans, bottles or food, with the rotatable handle in the upright position, the left side view being a mirror image thereof.

See application file for complete search history.

The portions of the serving tray for cans, bottles or food shown in broken lines form no part of the claimed design.
